Charles H. Strong & Edward A. Strong, of Norwich, Connecticut,

Letters Patent,

The schedule referred to in these Letters Patent and making part of the same containing a description in the words of the two Charles H. Strong & Edward A. Strong, themselves of this improvement in the mode of making Hoes, —

To all whom these presents shall come
Be it known that we, Charles H. Strong and Edward A. Strong of Norwich in the County of New London & State of Connecticut have invented a new and useful improvement in the mode of making Hoes called "Strong's improved Hoe" & that the following is a full & exact description of the construction of the said Hoe, as invented or improved by us, this improvement in making riveted eye, or braga eye hoes, consisting in sinking the shank of the eye, which eye is similar in shape, & position to that of the common or old fashioned welded eye hoe, its whole thickness into the under surface of the plate so as to leave the under surface of the hoe entirely smooth, thereby obviating two great objections, to the common riveted eye hoe which are, —

1st that the shank of the eye being placed on the outside of the plate, it always accumulate dirt, &c.

2nd that the hole of the eye is stuck in the plate (instead of being raised above the top of it) which brings the handle too near the ground. The hoe is to be made of rolled steel & the eye is to be secured with rivets or braga on, as the experiment may prove to be best.

The utility of the plan is this, a hole nearly the same in shape as the old fashioned or common welded eye & eye by strong or stronger can be made at a much less cost than the latter because they cannot easily be made of rolled steel, but the place of each hoe is separately hammered out after the eye

is melted on, -- We claim, that the plan of a rivet on a
brass cap, the head of which is plisse above the top of the head of
the shank, of which is sunk so thickly into the plate, as to
leave the under surface of the head smooth, & even is of our in-
vention. Research December 24. 1832,

Mitimus
